UNITED STATES PATENT OFFICE.

FRANK M. ROBY, OF CLEVELAND, OHIO.

LUBRICATOR.

Application filed April 6, 1922. Serial No. 550,096.

To all whom it may concern:

Be it known that I, FRANK M. ROBY, a citizen of the United States, residing at Cleveland, in the county of Cuyahoga and State of Ohio, have invented a certain new and useful Improvement in Lubricators, of which the following is a full, clear, and exact description, reference being had to the accompanying drawings.

10 This invention relates to lubricators of the type which are adapted to be mounted on a moving part of a machine and by impact of a suitably carried hammer gradually feed grease to a bearing. My lubricator is 15 especially well adapted, for instance, for mounting on side rods of locomotives.

The principal objects of the invention are to provide such a device in a form which shall be simple and inexpensive in construction, which shall retain its position when once installed, which shall visibly indicate its condition as to quantity of contained lubricant, and which shall normally remain closed, notwithstanding the jars incident to 25 operation, but which may be readily opened and resupplied with lubricant when desired.

Another feature is the provision of a convenient handle or tool for readily opening and closing the lubricator.

30 These and other features of the invention are hereinafter more fully explained in connection with the drawings, which show preferred embodiments of the invention.

In the drawings, Fig. 1 is a side elevation 35 of a pair of locomotive driving wheels, a connecting rod, and a parallel rod with my lubricators mounted on the end portions of the latter; Fig. 2 is a side elevation of one form of the lubricator with the grease follower in the position it has when the lubricator is empty; Fig. 3 is a plan of this form of lubricator; Fig. 4 is a vertical diametric section, on the plane indicated by the line 4—4 of Fig. 3, of the lubricator body, with the other parts removed; Fig. 5 is a vertical diametric section on the plane indicated by the line 5—5 of Fig. 3, this view showing the complete lubricator in the loaded position, and showing also a handle device which may be employed for removing the removable parts; Fig. 6 is a sectional side elevation of the movable parts when they have been removed from the body, and the handle device carrying the same; Fig. 7 is an edge

view of the handles shown in Figs. 5 and 6; Fig. 8 is a detail in horizontal section on the line 8—8 of Fig. 6, showing the relation of the handle lugs to the grease follower and the locking ring therefor; Fig. 9 is a side elevation of a modified form of lubricator, with the parts separated for convenience of illustration; Figs. 10 and 11 are horizontal sections on the correspondingly numbered lines of Fig. 9; Fig. 12 is a vertical diametric section through a portion of another modified form of lubricator; Fig. 13 is a plan of the embodiment shown in Fig. 12.

Referring first to Figs. 1 to 5 inclusive, 10 indicates the body of the lubricator, which is preferably a single integral casting, and 70 which is adapted to be permanently secured to the part of the machine which carries it, as for instance a locomotive side rod A. Such side rod has a cylindrical opening a in Fig. 5, leading to the crank pin, and the lubricator body is provided with a sleeve portion 11 adapted to occupy such recess a. The sleeve preferably has a portion of slightly enlarged diameter as 12, which may either make a snug fit with the wall of the 80 recess or may be threaded to screw thereinto, as desired. At the upper end of the sleeve portion is a lateral flange 14 which rests on the top of the rod or other carrying member and is preferably spot welded thereto, as indicated in Fig. 5. 85

Above the flange 14 the body has upwardly extending standards 15 of which there are preferably three, equally placed. Each standard merges below with the flange 14 and above with a ring-like portion 16 of the body. On the inner face of each standard is an upright rib 17, the inner surface of which aligns with the bore 18 of the sleeve portion 11. At the lower end of this sleeve portion 95 is formed an inwardly extending flange 19 which provides an inward limit for the grease follower. The space within the sleeve portion below the follower constitutes the grease receptacle, as will be readily understood. 100

The grease follower mentioned comprises a cylindrical tubular casing 30 and a lower head 31 secured thereto and freely slidable within the sleeve bore 18 of the body. This follower constitutes also the casing for the loose hammer 20, Fig. 5. As shown in this figure, the head 31, has a threaded hub 33

which screws into the interior of the hammer casing 30. A pin 34 passing through the sleeve wall and the threaded hub permanently lock these parts together with the hammer 5 loosely retained in the interior. At the upper end of the hammer casing is a head 35 closing the casing. This head, in the form illustrated in Figs. 1 to 8 inclusive, has projecting arcuate flanges 36 separated by 10 notches 37, to provide for engagement by a suitable removing device, as hereinafter explained.

40, in Figs. 2, 3, 5, 6 and 8, indicates a locking ring adapted to embrace the hammer casing 15 and engage the body to hold the parts in place and also to suitably compress a helical spring 50 surrounding the hammer casing and bearing at its upper end against the ring and at its lower end against the over- 20 hanging portion of the head 31. The ring 40 has outwardly extending wings 41 which are adapted to occupy downwardly facing recesses in the inner face of the ring portion 16 of the body, the upward pressure of the 25 spring retaining the ring in this position.

More specifically, as shown particularly in Fig. 4, the body ribs 17 are continued upwardly as at 60 about a considerably larger bore to the top of the body ring portion 16. 30 Adjacent such stop surface the body ring has internal arcuate horizontal ribs as indicated at 61 and at the end of these ribs are downwardly extending lugs 62, which project downwardly a material distance beyond that of the ribs 61 but not as far as the ribs 60. Between the rib 60 and the adjacent short vertical rib 62 are notches 65.

In installing the parts after the hammer casing with its spring is placed in the 40 body bore 18, the ring 40 is turned (if necessary to bring the wings 51 directly over the arcuate passageways 65) and then the ring is pressed downwardly, compressing the spring 50 until the wings are lower than 45 the bottom edge of the ribs 62 whereupon the ring is turned laterally a short distance until the wings pass beneath and beyond the ribs 62, whereupon on release of the pressure the ring may rise with its wings coming into the space between the ribs 62 and 50 60 as illustrated in Fig. 4.

It will be seen that the movement described effectively locks the parts in position, the follower being pressed downwardly 55 on the grease in the bore 18 by the spring 50 and the upward pressure of the spring maintaining the wings 41 in place in the recesses described, so that the ring can neither rotate nor move upwardly, nor does 60 it move downwardly until a suitable external pressure has been applied to it.

Fig. 2 shows the parts in the position just described. In use the position is the same except that the hammer casing extends 65 upwardly above the body a variable distance

as indicated in Fig. 1, dependent upon the amount of grease within the chamber 18. In opening the device for loading, the ring 40 is pressed downwardly until its wings 41 are lower than the bottom of the rib 70 62 and then is turned laterally until these wings are within the arcuate openings 65, when the ring, the hammer casing and the spring may be removed from the body to allow the installation of grease into the 75 chamber 18.

The ring is preferably permanently maintained on the hammer casing by means of the flanges 36 at the top of the casing heretofore mentioned, which overhang the ring, 80 and, as shown, may seat in a rabbet 43 in the upper surface thereof. Such a construction enables the entire top of the device to be flush when it is empty, as shown in Fig. 2, which has the advantage of enabling the 85 normally upwardly projecting hammer casing to form a convenient tell-tale indicating the amount of grease in the chamber. The ring preferably has notches 42 in its upper surface to enable a suitable tool to 90 conveniently rotate it.

Any suitable tool may be employed to press the ring 40 downwardly and give it a partial rotation necessary to free it. I have, however, illustrated in Figs. 5, 6 and 95 7 a convenient tool for this purpose, which is also adapted to easily draw out the hammer casing, with the hammer and spring, against the action of suction within the chamber 18. This device will now be described.

70 designates a suitable bail or looped handle having an upper horizontal reach and curved inwardly extending end portions. These end portions terminate in a 100 ring portion 71. This ring portion carries suitable lugs adapted to coact with the locking ring 40 and the flanges 36 of the hammer casing. These lugs designated 73, are shown as being portions of a ring member 105 having an outwardly extending annular flange 74 secured by screws 75 to the ring portion 71 of the handle member. The lugs 73 are L-shaped at their lower ends, projecting inwardly and then slightly downwardly as at 78. These inner portions 78 are adapted to extend through the notches 37 of the hammer casing head 35, and thereafter the under surface 77 of the lugs may seat against the ring 40 and shove it downwardly. In such position these lugs occupy 110 the notches 42, so that if the handle be turned, the ring 40 is thereby moved into position to clear the ribs of the body, and at the same time the inner extensions 78 pass beneath the arcuate ribs 36 of the hammer casing. Then the assembled movable parts may be drawn out and retained by the handle as shown in Fig. 6. The handle 115 may conveniently be provided with outer 120 125 130

lugs 79, preferably three in number to engage the outer surface of the body ring 16 and initially position the handle.

The downward extension of the end 78 below the ring abutting surface 77 enables the tool to be conveniently used to initially rotate the hammer casing to bring its notches 37 into registration with the notches 42 of the ring 40. As soon as this registration is effected, the parts are in position so that the removing tool may be pressed downwardly to carry the ring 40 inwardly to unlock it. Then, the turning of the handle a short portion of a rotation, frees the ring 15 and at the same time brings the L-shaped ends of the lugs 73 beneath the hammer casing flanges 36.

In operation of the device, assuming that the lubricator is installed and grease has 20 been supplied, the hammer casing normally extends above the top of the body, as shown in Fig. 1. Now, when the inspector sees that the top of the hammer casing is nearly or quite flush with the top of the body, he 25 knows it is time to supply additional grease. Thereupon, he places the removing tool over the lubricator with the ends of the lugs 73, of which three are shown, occupying the three notches 37 shown in 30 the head of the hammer casing; the under surfaces 77 of the lugs either cutting the notches 42 or riding on the ring 40 between these notches. The operator then, if necessary, turns the handle a short distance 35 (something less than one-third of a rotation) to bring the notches 37 into registration with the ring notches 42. He then presses downwardly on the removing tool to the limit of its possible movement, that is, 40 until stopped by the ring portion 71 abutting the casing body. He then turns the tool substantially one-third of a rotation in the left hand direction in the specific embodiment shown in Figs. 3 and 4. This 45 turns the ring so that its wings 41 clear the body ribs and at the same time brings the L-shaped ends 78 of the lugs 73 beneath the hammer casing head flanges 36. The operator then pulls outwardly on the handle removing the hammer casing, hammer, spring and locking ring.

Having now removed all the removable parts, the operator inserts the desired quantity of grease into the body chamber 18. 55 This is most conveniently done by dropping a grease cartridge into said chamber. If the quantity of grease inserted extends materially above the top of the chamber 18, it may be conveniently pushed or wiped out 60 through the openings between the standards 15.

After renewing the grease supply, the operator returns the hammer casing to the body, shoving it downwardly against the 65 grease by pressure on the handle, which has

preferably been retained in engagement with it. When the hammer casing is being returned, the inner surfaces of the ribs 17 form convenient guides for directing its lower ends into position in the chamber 18. 70 If the quantity of grease inserted is not excessive, the operator may then shove downwardly on the handle until the wings 41 of the ring pass to the bottom of the body notches 65, whereupon rotation in the right 75 hand direction for substantially one sixth of a turn, brings the wings 41 beyond the ribs 62, and the same movement brings the lugs 73 into registration with the hammer casing notches 37, so that when the pressure is released, the spring 50 returns the ring 40 to normal position and leaves the removing tool simply resting on the lubricator free to be removed.

If too large a quantity of grease is placed 85 in the receptacle, so that the operator cannot force down the ring manually sufficiently to lock it, this will become evident by the fact that the central portion 70 of the handle abuts the top of the hammer casing. 90 The operator may then either remove some of the grease or, if he desires, may by hammer strokes on the top of the handle 70, drive the hammer casing further down into the receptacle to shove the grease ahead of 95 it a sufficient distance to enable the ring to be locked.

Figs. 9, 10 and 11 I have illustrated as a somewhat different embodiment of the lubricator. In this case, the locking ring, instead 100 of seating within the body, is made external and passes over it and cooperates with external ribs on it. The locking however, is effected by the same manner as heretofore described by interacting lugs which are normally retained in locked position by the spring 50.

As shown in these figures, the body 10^a has its lower portion as heretofore described, but above the horizontal flange 14 it is 110 formed simply with a short upward sleeve portion 80 of sufficient size to house the hammer casing 30 and the spring 50, this sleeve portion having at its upper end three equidistant arcuate outwardly extending ribs 81. 115 The locking ring in this instance comprises a cap 90 having a top portion 91 with a hole through which the hammer casing passes and a downwardly extending skirt 92. The spring 50 bears at its upper end against the 120 inner face of the cap top 91, and the parts are retained permanently by a flange 100 on the hammer casing, which seats within a rabbet in the top 91. The skirt 92 has at its lower edge three inwardly projecting arcuate portions 95 each of which terminates in two upwardly extending lugs 96.

Fig. 9 shows the parts of this modification as it is being loaded. Sufficient rotation of the cap 90 brings the ribs 95 into 130

registration with the spaces between the ribs 81 of the body; then downward pressure on the cap carries the ribs 95 and their up-standing lugs 96 below the ribs 81; then substantially one-sixth of a rotation carries the portions 95 of the cap directly beneath the lugs 81 with the two ribs 96 in position beyond the ends of such lugs; then, as the pressure is relieved, the spring 50 raises the cap so that each pair of lugs 96 embraces one of the ribs 81, while the intermediate cap lugs 95 abut the lower faces of such rib 81. This effectively locks the cap to the body.

The hammer casing in this instance is shown as provided with a head 101 above the flange 100, the casing being annularly recessed at 102 beneath the head 101. This overhanging head provides a convenient device for engagement of a suitable tool, as some kind of a jaw clamp for instance, to remove the hammer casing from the grease chamber against the suction tending to retain it. The cap in this illustration may conveniently be depressed and rotated as desired by the hand of the operator.

In Figs. 12 and 13, I have illustrated another modification of the device still embodying the same general principles. In this view, the body member 10⁰ is very similar to the body member of Fig. 2, though the top ring 116 is of slightly less depth than the ring portion 16, and the standards 115 are formed slightly differently from the standards 15. The top ring however, has an inwardly projecting portion 161 separated by arcuate recesses 165 and each inwardly projecting portion carries on its under side downwardly extending ribs 160 and 162. The locking ring in this instance, has a greater vertical extent than the ring 40 of Figs. 2 and 3, but has outward arcuate wings 141 and top notches 142 corresponding to the wings and notches 41 and 42.

The hammer casing in this instance is shown as having a lateral flange 130 overhanging the top of the ring 140 and lying within the rabbet provided by the arcuate ribs on the opposite sides of the notches 142. The upper end of the hammer casing is preferably formed with an eye 133 furnishing convenient means for the engagement of a suitable tool to withdraw it. Some suitable tool (which may, of course be combined with the tool which engages the eye 153) serves to engage the notches 142 and push the ring inwardly and give it a portion of a rotation to free it.

It will be seen that in all the embodiments of the invention described, the essential locking feature is the same, namely, there is a movable ring acted on by the spring and having lugs which may be brought into co-action with, or released from the lugs on the body by longitudinal and separate rotary movements of the ring. The longitudi-

nal movement of the ring is in each instance against the action of the spring and the reaction of the spring serves to retain the ring in locked position. In other words, in each instance, the ring is forced downwardly against the action of the spring sufficiently to clear the body lugs and is then given a partial rotation and then returned partway, into locked position. Other specific constructions embodying this general locking principle may be readily devised and I do not intend to limit myself to any of the embodiments shown, except in such claims as plainly so indicated.

The construction of the hammer casing may also be modified from that shown, and still obtain the same general result. The two parts of the hammer casing are made separable to enable a ready installment of the hammer. This separation however, need not take place at the lower end as shown in Fig. 5, but may be made at any part of the hammer casing,—at the lower end, upper end or at some intermediate portion. It is desirable however, after the hammer has been installed, that the separable parts of the hammer casing be permanently secured together.

Having thus described my invention, I claim:—

1. In a lubricating device, the combination with a lubricant receptacle, of a lubricant follower, and means associated with the follower to removably retain the follower in active position, said means being operative on an axially inward and outward movement to lock the follower.

2. In a lubricating device, the combination with a lubricant receptacle, of a lubricant follower movable therein, and co-operating means between the follower and receptacle for removably retaining the follower in active position, said means including a member having an axially in and out motion relative to said receptacle.

3. In a lubricating device, the combination with a lubricant receptacle, of a lubricant follower carried thereby, and means associated with the receptacle and follower for removably retaining the follower in active position within the receptacle, said means being operative on an axially inward and outward motion relative to the receptacle for locking the follower.

4. In a lubricating device of the class described, the combination with a lubricant receptacle, of a lubricant follower therein, a member associated with the follower and receptacle for locking the follower in active position to the receptacle, said member being operative on an axially in and out motion relative to the receptacle.

5. In a lubricator, the combination of a body having a grease receptacle, a hammer casing containing a loose hammer and

- adapted to occupy the receptacle, a spring and a locking member acted on by the spring and normally retained by it in engagement with the body.
5. In a lubricator, the combination of a body having a grease receptacle, a hammer casing containing a loose hammer and adapted to occupy the receptacle, a helical compression spring surrounding the hammer casing, and a locking member pressed upwardly by the spring and normally retained by it in engagement with the body.
10. In a lubricator, the combination of a body adapted to be secured to a part to be lubricated, and having a bore constituting a lubricant receptacle, a hammer casing extending into the lubricant receptacle, a loose hammer within the casing, said hammer casing having at its lower end an enlarged head slidably engaging the bore of the body, a ring embracing the hammer casing, a helical spring surrounding the hammer casing and compressed between said enlarged head and said ring, and means for locking the ring to the body.
15. In a lubricator, a body adapted to be secured to a part to be lubricated and having a lubricant receptacle, a tubular hammer casing containing a loose hammer and closed at its upper and lower ends, said casing occupying the body, a ring embracing the casing, the casing having a projection above the ring limiting the outward movement of the ring and having a head at its lower end, a spring surrounding the casing and compressed between said head and said ring, and means for securing the ring to the body.
20. In a lubricator, a body adapted to be secured to a part to be lubricated and having a lubricant receptacle, a lubricant follower occupying the body, a ring embracing the follower, said follower having a projection above the ring limiting the outward movement of the ring and having a head at its lower end, a spring surrounding the follower and compressed between said head and said ring, the ring and body having coacting arcuately separated lugs adapted to be brought into engagement by inward movement and subsequent rotative movement and subsequent outward movement of the ring, and one of said members having longitudinal lugs to prevent further rotative movement of the ring after the first mentioned lugs have come into engagement.
25. In a lubricator, the combination of a body having an internal chamber, a follower adapted to occupy said chamber, a ring for locking the follower to the body while allowing longitudinal movement of the follower, and a spring serving the double purpose of urging the follower downwardly and the locking ring upwardly into locked engagement.
30. In a lubricator, the combination of a body having an internal chamber, a follower adapted to occupy said chamber, means for locking the follower to the body while allowing longitudinal movement of the follower, and a spring serving the double purpose of urging the follower downwardly and retaining the locking means active, said body having an inward projection limiting the inward movement of the follower.
35. In a lubricator, the combination of a body having an internal chamber, a hammer casing adapted to occupy said chamber, a loose hammer within the casing, a ring for locking the hammer casing to the body while allowing longitudinal movement of the hammer casing, a spring serving the double purpose of urging the hammer casing downwardly and the locking ring upwardly into locking engagement, said body having an inward projection adjacent its inner end limiting the inward movement of the hammer casing.
40. In a lubricator, the combination of a body having a lubricant chamber, a hammer casing adapted to occupy said chamber and having top and bottom heads, a ring surrounding the hammer casing between said heads, a spring surrounding the hammer casing and compressed between the lower head and the inner face of the ring, coacting lugs on the body and ring whereby the ring may be held to the body by an outward action of the spring but freed therefrom by inward pressure plus a rotative movement, and a shoulder at the inner end of the body limiting the inward movement of the hammer casing and preventing the same normally passing inwardly far enough to set free the spring.
45. In a lubricator, the combination of a body having a lubricant chamber, a follower adapted to occupy said chamber, a ring surrounding the follower, a spring bearing

- against the inner face of the ring, coacting lugs on the body and ring whereby the ring may be held to the body by the outward action of the spring, but freed therefrom by inward pressure plus a rotative movement, there being means on the upper end of the follower for enabling its engagement by a suitable tool whereby it may be withdrawn. 16. In a lubricator, the combination of a body having a lubricant chamber, a hammer casing adapted to occupy said chamber, a loose hammer within the casing, a ring surrounding the hammer casing, a spring surrounding the hammer casing and compressed against the inner face of the ring, coacting lugs on the body and ring whereby the ring may be held to the body by the outward action of the spring, but freed therefrom by inward pressure plus a rotative movement, there being means on the upper end of the hammer casing for enabling its engagement by a suitable tool whereby it may be withdrawn. 17. In a lubricator of the class described, the combination of a body having a downward extension adapted to seat within a member to be lubricated and having an outward flange above such portion, and an upward extension above the flange, said upward extension being provided with spaced lugs, a locking ring having spaced lugs adapted to pass downwardly between the lugs of the body and to be rotated to pass beneath the same, one of said members having longitudinally extending lugs to engage the edge of the lugs on the other member and thereafter prevent rotation of the ring, a lubricant follower, and spring means acting downwardly on the follower and upwardly on the ring. 18. In a lubricator of the class described, the combination of a body having a downward extension adapted to seat within a member to be lubricated and having an outward flange above such portion and an upward extension above the flange, said upward extension being provided with spaced arcuate lugs, a locking ring having spaced arcuate lugs adapted to pass downwardly between the lugs of the body and to be rotated to pass beneath the same, one of said members having longitudinally extending lugs to engage the arcuate ends of the lugs on the other member and thereafter prevent rotation of the ring, a hammer casing, a loose hammer therein, a spring surrounding the casing and acting downwardly thereon and upwardly on the ring, said casing having a projection above the ring, and a projection below the spring. 19. In a lubricator of the class described, the combination of a body adapted to be secured to a part to be lubricated, a hammer casing made in separable parts and containing a loose hammer, said casing being a closed unit in use and having upper and lower heads, a locking ring embracing the casing beneath the upper head and adapted to coact with the body, a helical compression spring between the lower head and ring, and an inward flange at the lower end of the body adapted to limit the inward movement of the hammer casing. 20. The combination with a lubricant having a body, a lubricant follower, a locking ring coacting with the body by reason of longitudinal movement and rotative movement of the ring, and a tool adapted to press the ring inwardly and thereafter partially rotate it. 21. The combination with a lubricator having a body, a lubricant follower, a locking ring coacting with the body by reason of longitudinal movement and rotative movement of the ring, a tool adapted to press the ring inwardly and partially rotate it, and means on the follower which such tool may engage to withdraw it from the lubricator. 22. The combination with a lubricator having a body, a lubricant follower, a locking ring coacting with the body by reason of longitudinal movement and rotative movement of the ring, and a tool adapted to press the ring inwardly and partially rotate it, and means whereby the tool may withdraw the follower and ring as a unit. 23. The combination with a lubricator having a body, a lubricant follower, a locking ring coacting with the body by reason of a spring surrounding the follower and compressed between a projection thereon and the ring, a tool adapted to press the ring inwardly and partially rotate it, and means whereby such tool may withdraw the follower spring and ring as a unit. 24. The combination with a lubricator having a body, a movable lubricant hammer and a casing therefor, a locking device for the movable parts, and a tool adapted to unlock the lubricator and remove the casing and hammer. 25. In a lubricating device of the class described, the combination of a body, a reciprocating hammer, and means to removably retain the hammer in active position, comprising a locking member locked to the body by a combined longitudinal and separate rotative movement of the locking member. 26. In a lubricating device of the class described, the combination of a body, follower spring pressed against the lubricant, and means to removably retain the follower in active position, comprising a locking member engaging the follower and locked to the body by a combined inward and outward and rotative movement. 27. In a lubricator of the class described, the combination of a body adapted to contain lubricant, a hammer casing longitudinally movable therein and a locking member en-

gaging the hammer casing and the body, said locking member and body having coacting lugs brought into engagement by a combined longitudinal and rotative movement of the locking member.

28. In a lubricator of the class described, the combination of a body adapted to contain lubricant, a hammer casing longitudinally movable therein, a locking member engaging 10 the hammer casing and the body, said locking member and body having coacting lugs adapted to be brought into locking engagement by a combined longitudinal and rotative movement of the locking member, 15 and a spring acting on the locking member to normally retain such engagement.

29. The combination with a body having a lower portion and an upper portion, the lower portion being adapted to be secured 20 to a part to be lubricated, and the upper portion extending above said part, spaced ribs connecting the upper and lower members of the body, a hammer casing containing a loose hammer and carried by said body and 25 guided by said ribs, a locking member associated with the upper portion of the body, and a spring serving the double purpose of

urging the casing in one direction and the locking member in the opposite direction into locked engagement with the body.

30

30. In a lubricator, the combination with a body having a lower portion and an upper portion, spaced ribs connecting said portions, a hammer casing disposed within the body and guided by the ribs, a locking member associated with the casing and the upper portion of the body, and a spring acting upon said casing and member to urge the casing into the body and force the member into locked position, said ribs providing an open 40 space intermediate the upper and lower portions whereby excessive lubricant may be removed.

35

31. The combination with a lubricator having a body, of a removable lubricant 45 hammer, a casing therefor, a locking ring associated with the casing and body, and means for rotating said ring to unlock the lubricator and remove the casing and ham- 50 mer.

In testimony whereof, I hereunto affix my signature.

FRANK M. ROBY.
